US00D795961S

(12) United States Design Patent (10) Patent No.: US D795,961 S
(45) Date of Patent: * Aug. 29, 2017

(54) CONTROLLER

(71) Applicant: Microsoft Corporation, Redmond, WA (US)

(72) Inventors: Monique Chatterjee, Seattle, WA (US); Richard T. Hanks, Seattle, WA (US); William Bennett Mabry, Seattle, WA (US); Austin Porter, Seattle, WA (US)

(73) Assignee: Microsoft Corporation, Redmond, WA (US)

() Term: 15 Years

(21) Appl. No.: 29/578,412

(22) Filed: Sep. 21, 2016

Related U.S. Application Data

(63) Continuation of application No. 29/571,165, filed on Jul. 14, 2016.

(51) LOC (10) Cl. 21-01

(52) U.S. Cl.

USPC D21/333; D14/401

(58) Field of Classification Search

USPC ..... D14/496, 401, 435, 474, 483, 217, 137, D14/138, 160, 168, 356, 203.1–203.8, D14/507; 345/156, 169, 173–179, 905; 715/727–729, 864, 700, 706, 719; 710/1, 710/5, 8; 713/1, 600; 455/1.1, 1.7, 73, 455/344–347, 93, 95, 3.01–3.06, 550.1, 455/573.1; 370/342–344; 369/1, 2, 369/6–12; 463/51–57, 40–47, 1, 29–35; D21/324, 328, 333; 273/148 B

CPC .. A63F 13/00; A63F 13/02; A63F 9/00; G06F 17/00; G06F 19/00

(57) CLAIM

The ornamental design for a controller, as shown and described.

DESCRIPTION

FIG. 1 is a front perspective view of a controller showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the remainder of the controller in FIGS. 1–7 is for environmental purposes only and forms no part of the claimed design.

1 Claim, 7 Drawing Sheets
